SUCTION NOZZLE

Gustaf Einar Lofgren, Riverside, Conn., assignor
to Electrolux Corporation, New York, N. Y., a
corporation of Delaware

Application November 28, 1939, Serial No. 306,448

9 Claims. (Cl. 285—97.3)

My invention relates to suction nozzles and more particularly to a suction nozzle of the type connected to a suction producing device by a flexible hose or conduit.

An object of my invention is to provide an improved suction nozzle, in which the handling of the nozzle is facilitated by a pivotal connection.

A further object of my invention is to provide an improved nozzle which may be readily assembled and is of simple construction.

What I consider to be novel and my invention may be better understood by reference to the following specification and appended claims when considered in connection with the accompanying drawings, in which

Fig. 1 is a front view of my improved suction nozzle cut away in part to show the internal construction;

Fig. 2 is a sectional view taken along the line 2—2 of Fig. 1;

Fig. 3 is a detail sectional view taken along the line 3—3 of Fig. 2;

Fig. 4 is an exploded view showing parts of the suction nozzle in position for assembly;

Fig. 5 is a sectional view similar to Fig. 2 showing a modified form of construction;

Fig. 6 is a view showing the suction nozzle cut away in part to expose the swivel construction;

Fig. 7 is a detail sectional view taken along the line 7—7 of Fig. 5; and

Fig. 8 is a perspective view of a friction spring.

Referring to the drawings, 10 indicates generally a suction nozzle having a base 11 and a top cover member 12. Base 11 has a central suction opening 13. Along the front and rear edges of base 11, brush bristles 14 are secured in recesses 15 provided therefor. Extending around the outer edges of base 11 is a rubber bumper 16, which is positioned between the base 11 and the top cover 12. The cover 12 is secured to the base 11 by means of screws 17. Two spaced socket members 18 and 19, as best indicated in Fig. 4, are secured to the base 11. A strap 20 connects the tops of the socket members 18 and 19 to hold them in spaced relation.

Socket members 18 and 19 are adapted to receive an elbow 21, provided for the connection of a tubular hose, or conduit member, communicating with a source of suction. Elbow 21 is substantially a 45 degree elbow with a portion 22 extending within the socket members 18 and 19. The interior of elbow 21 is connected to the suction opening 13 by means of a hood 23 secured to base 11. Hood 23 has a turned over edge 24 engaging a shoulder 25 on socket 18 for providing an air tight connection to the elbow 21. The portion 22 of elbow 21 is provided with an annular recess 26. A substantially U-shaped spring

member 27 engages elbow 21 to produce a resistance by means of friction to free movement of elbow 21 and to hold it in any desired position with respect to the nozzle 10. Spring member 27, in addition to providing a frictional means for holding the elbow 21 in a particular position, also locks the elbow 21 to the socket members 18 and 19 by extending into the annular recess 26.

10 In the assembly of the suction nozzle, as best indicated in Fig. 4, the socket members 18 and 19 and the hood 23 are first secured to the base 11. The elbow 21 is then inserted with the portion 22 extending through the socket members 18 and 19. The spring 27 is snapped in position in the recess 26. The cover member 12 is then secured to the base 11 by the screws 17 with the bumper 16 located in position between the outer edges of the base 11 and cover 12. The brush bristles 14 may be inserted in the base 11 either before or after the above assembly is completed.

25 In a modified form of construction, as shown in Figs. 5 to 8, a narrow annular recess 28 is provided in the portion 22 of the elbow 21. A split ring 29 is located in the recess 28. A spring member 30 is located between the bottom of the portion 22 of elbow 21 and the base 11. Spring 30 is provided with a longitudinal slot 31 which is adapted to receive the ring 29. In this construction, the locking of the elbow to the base 11 is accomplished by the combination of the split ring 29 and the spring 30. The frictional contact for holding the elbow in a selected position with respect to the base 11 is accomplished by the spring 30.

30 The assembly of this construction is substantially the same as the assembly of the form of the invention illustrated in Figs. 2 to 4, with the difference that the split ring 29 is located on the elbow 21 before it is inserted in position, and the spring 30 may be positioned either before or after the elbow 21 is inserted in the socket members 18 and 19. The springs 27 and 30 in the two forms of construction make it possible to provide a relatively free movement between the elbow 21 and the sockets 18 and 19, so that it is not necessary to hold these parts to close tolerances. If it were necessary to hold these parts to close tolerances, considerable difficulty would be experienced in binding when the minimum tolerances were obtained. The combination of the springs 27 and 30 with the annular recess 26 and the split ring 29 also serve to lock the parts together and prevent relative longitudinal movement between the elbow 21 and the base 11. The springs 27 and 30 must engage the elbow 21 with sufficient force to prevent accidental or unintentional movement of the elbow 21 with respect to the base 11. Movement between the elbow 21

and the base 11 is desirable to permit the insertion of the suction nozzle beneath a low piece of furniture or in relatively confined quarters.

While my invention has been illustrated in specific embodiments, it must be understood that the invention is not limited to the exact construction illustrated, but variations may be made within the scope of the appended claims.

What I claim is:

1. In a suction nozzle, a base having an opening, a first socket member secured to said base, a second socket member secured to said base in spaced relation to said first socket member, a hood secured to said base communicating with said opening and with the interior of said first socket member, an elbow journaled in said socket members, and means for locking said elbow to said socket members comprising a spring frictionally engaging said elbow and fixed with respect to said base adapted to restrain relative rotation therebetween.

2. In a suction nozzle, a base having an opening, a first socket member secured to said base, a second socket member secured to said base in spaced relation to said first socket member, a hood secured to said base communicating with said opening and with the interior of said socket member, an elbow journaled in said socket members and having an annular external recess, locking means located in said recess and positioned between said socket members, and a spring frictionally engaging said elbow and fixed with respect to said base adapted to restrain relative rotation therebetween.

3. In a suction nozzle, a base having an opening, a first socket member secured to said base, a second socket member secured to said base in spaced relation to said first socket member, a hood secured to said base communicating with said opening and with the interior of said first socket member, an elbow journaled in said socket members and having an annular external recess, a ring seated in said recess and positioned between said socket members, and a spring frictionally engaging said elbow and fixed with respect to said base adapted to restrain relative rotation therebetween.

4. In a suction nozzle a hollow body having a coupling opening and a suction inlet adapted to be placed over a surface to be cleaned, an elbow pipe body having a coupling opening and an outlet adapted to be placed in communication with a source of suction, means for coupling said bodies to form a continuous passage from one body to the other, and spring friction means engaging said bodies, said friction means and said first-mentioned means co-operating to permit relative rotation of said bodies only when the frictional force produced by said friction means is overcome.

5. A hollow body having an inlet and an outlet, a second hollow body having an inlet and an outlet, ring-shaped socket members fixed to one of said bodies over its outlet spaced apart axially from one another, the inlet end of the other body lying within said socket members and having an annular external recess in alignment with the space between said socket members, and means comprising a ring segment lying in said recess having a projection beyond the recess into the annular space between the socket members and a spring fixed with respect to said socket members having a portion projecting into said annular space and pressing against the inlet end

of said other body, said means permitting relative rotation between said bodies only when the frictional force between the spring and said other body is overcome.

6. A suction cleaning tool comprising a hollow body having a coupling opening and a suction inlet adapted to be placed over a surface to be cleaned, an elbow pipe body having a coupling opening and an outlet adapted to be placed in communication with a source of suction, ring-shaped socket members fixed to one of said bodies over its coupling opening spaced apart axially from one another, the coupling opening end of the other body lying within said socket members and having an annular external recess in alignment with the space between said socket members, and means comprising a ring segment lying in said recess having a projection beyond the recess into the annular space between the socket members and a spring fixed with respect to said socket members having a portion projecting into said annular space and pressing against the coupling opening end of said other body, said means permitting relative rotation between said bodies only when the frictional force between the spring and said other body is overcome.

7. A hollow body having an inlet and an outlet, a second hollow body having an inlet and an outlet, ring-shaped socket members fixed to one of said bodies over its outlet spaced apart axially from one another, the inlet end of the other body lying within said socket members and having an annular external recess in alignment with the space between said socket members, and means comprising a spring fixed with respect to said socket members having a portion projecting through said annular space and pressing against said recess, said means permitting relative rotation between said bodies only when the frictional force between the spring and said other body is overcome.

8. In a suction nozzle a hollow body having a coupling opening and a suction inlet adapted to be placed over a surface to be cleaned, an elbow pipe body having a coupling opening and an outlet adapted to be placed in communication with a source of suction, means for coupling said bodies to form a continuous passage from one body to the other, and spring friction means engaging said bodies, said friction means and said first-mentioned means co-operating to permit relative rotation of said bodies only when the frictional force produced by said friction means is overcome, said coupling means comprising a female part mounted on the hollow body and supported in addition to its connection to the coupling opening of the hollow body by means directly connected to the suction inlet.

9. In a suction nozzle a hollow body having a coupling opening and a suction inlet adapted to be placed over a surface to be cleaned, an elbow pipe body having a coupling opening and an outlet adapted to be placed in communication with a source of suction, means for coupling said bodies to form a continuous passage from one body to the other, and spring friction means engaging said bodies, said friction means and said first-mentioned means co-operating to permit relative rotation of said bodies only when the frictional force produced by said friction means is overcome, and a member secured to one of said bodies adapted to cover said coupling and said spring friction means.

GUSTAF EINAR LOFGREN.
